[57] CLAIM

The ornamental design for a dry shaver, as shown and described.

DESCRIPTION

FIG. 1 is a top, front, and right side perspective view of a dry shaver showing our new design;
FIG. 2 is a front elevational view thereof;
FIG. 3 is a rear elevational view thereof;
FIG. 4 is a right side elevational view thereof, the left side being a mirror image;
FIG. 5 is a top plan view thereof;
FIG. 6 is a bottom plan view thereof;
FIG. 7 is a top, front and right side perspective view showing a modification of the dry shaver of FIG. 1;
FIG. 8 is a front elevational view of FIG. 7;
FIG. 9 is a rear elevational view of FIG. 7;
FIG. 10 is a right side elevational view of FIG. 7;
FIG. 11 is a left side elevational view of FIG. 7;
FIG. 12 is a top plan view of FIG. 7;
FIG. 13 is a bottom plan view of FIG. 7;
FIG. 14 is a top, front and right side perspective view showing a second modification of the dry shaver of FIG. 1;
FIG. 15 is a front elevational view of FIG. 14, the rear view being the same as FIG. 9;
FIG. 16 is a right side elevational view of FIG. 14;
FIG. 17 is a left side elevational view of FIG. 14;
FIG. 18 is a top plan view of FIG. 14; and
FIG. 19 is a bottom plan view of FIG. 14.
